UNITED STATES PATENT OFFICE.

GILMORE W. BRANT, OF CANTON, OHIO.

RAIL-JOINT BOX.

1,386,685.

Specification of Letters Patent. Patented Aug. 9, 1921.

Application filed September 7, 1920. Serial No. 408,409.

To all whom it may concern:

Be it known that I, GILMORE W. BRANT, a citizen of the United States, residing at Canton, in the county of Stark and State of Ohio, have invented a new and useful Rail-Joint Box, of which the following is a specification.

This invention relates to a rail joint box especially adapted for use at rail joints 10 upon paved streets.

The objects of the invention are the provision of a box at each rail joint, a removable lid being provided upon said box whereby access may be quickly and readily had to the rail joint in order to tighten the bolts; the box being located in the paving, the necessity of tearing up the paving around each joint at frequent intervals in order to tighten the bolts at the joint, and to ballast under the ties, being thus obviated.

With these objects in view the invention consists in the novel construction and arrangement of parts hereinafter described illustrated in the accompanying drawings 25 and pointed out in the appended claims, it being understood that various changes in the form, proportion and details of construction may be made without departing from the invention.

30 In the accompanying drawings;

Figure 1 is a plan view of a section of railway track showing the rail joint applied thereto,

Fig. 2 a transverse sectional view through the joint provided with a box embodying the invention,

Fig. 3 a perspective view of the box; and Fig. 4 a plan view of the same.

Similar numerals of reference indicate 40 corresponding parts throughout the several views.

Referring to the construction illustrated in the accompanying drawing the rails such as are often used upon street railways which 45 are located on paved streets, are indicated by the numeral 1.

The splice-pieces 3 and 4 are of the usual construction with the exception that the splice-piece 3 is provided with a horizontal flange 5 which extends beyond the edge of the rail head, while the splice-piece 4 is provided with an upwardly disposed flange 6 arranged to engage the adjacent side of the rail head. The usual bolts 7 are provided 55 for connecting the ends of adjoining rails to the splice-pieces.

Boxes 8 and 9 are placed upon the ties 10, each of said boxes having an open side located toward the adjacent splice-piece, thus making the bolts and nuts accessible through 60 said boxes. The box 8 is similar to the box 9 with the exception that the end walls thereof are shaped to conform to the removable cover plate 11 which is off-set as shown at 12 in order that the inner edge thereof may 65 rest upon the flange 5 of the adjacent splice-piece, screws 13 or the like being provided for detachably connecting the off-set edge of the cover plate to said flange.

The cover plate 14 upon the box 9 is arranged to be positioned upon the top of the box flush with the head of the rail and with the surrounding paving 15, the inner edge of said cover plate resting upon the flange 6 of the adjacent splice-piece, screws 13 being provided for detachably connecting the cover plate to the splice-piece. Each of the cover plates is provided with a longitudinal rib 16 upon its outer edge arranged to engage a corresponding groove 17 in the outer 80 wall of the box, these ribs and grooves, in connection with the screws 13, holding the cover plates securely in place upon the boxes. The bottom wall of each box is provided with an enlarged opening 18 through which 85 access may be had to the ties and the ballast.

A hook portion 19 is provided upon the inner edge of each end wall of each of the boxes and arranged to engage the adjacent 90 splice-piece as best shown in Figs. 3 and 4, the upper rib of each splice-piece being cut away at each end as shown at 20 in order to allow said hook portions to be positioned around the ends of the splice-piece.

From the above description and an inspection of the accompanying drawings it will be evident that a device is provided which may be easily installed at a small cost and by means of which access may be readily had to the bolts 7 whenever it becomes necessary to tighten said bolts. With the usual form of track construction now in use upon paved streets, it is necessary to tear up the paving surrounding each rail joint, at frequent intervals, in order to tighten the bolts which are provided at the rail joints as the continual wear upon the tracks causes the bolts to loosen. With the present construction it is only necessary to remove the screws 110 13 and lift the cover plates from the boxes in order to have access to the bolts and

the nuts thereon, it not being necessary to tear up any of the paving surrounding the rail joint.

I claim:—

- 5 1. In combination with a rail joint surrounded by paving, a box open upon its inner side, hooks upon opposite ends of said open side arranged to be hooked around the ends of a splice-piece of the joint to hold the
10 box in position and a removable cover for the box.
2. In combination with a rail joint sur-

rounded by paving, a box open upon its inner side and connected to a splice-piece of the joint, one wall of the box having an interior, horizontal groove near its upper edge and a removable cover having a rib upon one edge arranged to be seated in the said groove, the opposite edge portion of the cover being connected to the upper edge of the adjacent wall of the box.

In testimony that I claim the above, I have hereunto subscribed my name.

GILMORE W. BRANT.
